UNITED STATES PATENT OFFICE.

EDWIN RUTHVEN WHITNEY, OF ST. JOHNSBURY, VERMONT.

CUT-OUT FOR INCANDESCENT ELECTRIC LAMPS.

SPECIFICATION forming part of Letters Patent No. 401,527, dated April 16, 1889.

Application filed July 21, 1888. Serial No. 280,675. (No model.)

To all whom it may concern:

Be it known that I, EDWIN RUTHVEN WHITNEY, of St. Johnsbury, in the county of Caledonia and State of Vermont, have invented 5 certain new and useful Improvements in Automatic Cut-Outs for Incandescent Electric Lamps; and I do hereby declare that the following is a full, clear, and exact description of the same.

10 This invention relates to the cut-outs employed in incandescent lamps for maintaining the closed circuit, and refers more particularly to those lamps which are provided with an auxiliary high-resistance lamp on an alternate circuit capable of being cut in by means of electro-magnetic devices, &c.

The object of the invention is to dispense with the use of any such electro-magnetic devices and with the high-resistance lamp or 20 heavy-resistance coils, as the case may be, and substitute for them a device in the form of a gravity-drop operated by the fusing of a strip of metal situated between and connected with two high-resistance carbons forming part of a 25 temporary branch circuit for the current when obstructed in its proper course for connecting the terminals of an alternate branch circuit from the main line, and so allow the current uninterrupted flow, the device being contained in an auxiliary lamp in order to protect the carbons and the drop being suspended by a wire from the top of the lamp. In connection with this cut-out, and in order to secure a simple, well-insulated, and efficient 30 holder with the necessary triple terminal connections, respectively, for main-line wires, wires to terminals of lamp proper, and wires to terminals of branch running through auxiliary lamp containing the operating parts of 35 40 cut-out, I use a flat body of non-conducting material, and on opposite ends of this I secure three armed metal connecting-pieces, preferably covered with rubber tubing, the arms projecting, respectively, upward, downward, and outward, and having their ends split to receive the wires mentioned, which are then held in place by thumb-sleeves of non-conducting material screwed on and compressing such ends. The key for cutting the 45 50 lamp in and out by hand is arranged on the face of the body of the holder, and is preferably formed of a flat strip of spring metal

faced with rubber or other insulator pivoted at one end to a stud screwed through a portion of the body into contact with the metal 55 connecting-piece on one side of same, its opposite or free end making connection when desired with a metal contact-latch communicating with the other metal connecting-piece. A coiled spring encircles the stud and has 60 one end connected to the body and the other to the key, thus insuring a very sudden lift from the latch when disengaged therefrom, and so obviating the chance of "sparking." For full comprehension, however, of the invention reference must be had to the annexed drawings, in which—

Figure 1 shows a front view of holder, lamp proper hung therefrom, with shade in section, and auxiliary lamp containing operating parts 70 of cut-out mounted thereon. Fig. 2 is a sectional plan view taken on line *xx*, Fig. 1, with glass bulb of auxiliary lamp omitted. Fig. 3 is a vertical sectional detail of portion of metal connecting-piece with which the metal 75 key-latch communicates, and Fig. 4 is a vertical section of an entire connecting-piece, showing screw-sleeves in place.

Similar letters of reference indicate like 80 parts.

A represents the non-conducting body of the holder; *A'*, portion of bracket by which it is supported; *B*, the lamp proper, with the usual terminals, *b b*; *C*, the auxiliary lamp, containing the operating parts of the automatic cut-out; and *D* the shade, of any ordinary kind, hung from the bottom of holder *A*.

P and *N* are the metal connecting-pieces, secured by screws *p n* on opposite ends of body *A* (suitably recessed to receive them) 90 and formed, respectively, with three arms, *1^p* *2^p* *3^p* and *1ⁿ* *2ⁿ* *3ⁿ*, whose ends are split to receive, respectively, the main-line wires *m m*, wires or strips of metal, *ll*, leading to terminals *b b* of lamp proper, and the same, *c c*, leading 95 to the auxiliary lamp. The ends of these arms are also screw-threaded to receive the screw-sleeves *P' N'*, which serve, when screwed fully upon, to compress them, and so hold the wires in place.

E represents the insulating material, preferably rubber tubing, covering the connecting-bars.

Coming now to the operating parts of the

cut-out, F F' are the platinum terminals, connected to the metal strips c c outside the glass bulb, and carrying on their inside upper ends arms furnished with socket-contacts G G at 5 one end.

H is a central hanging wire sealed into the top of the lamp, as shown, and having a strip, H', of fusible metal inserted about midway in its length. To the lower end of H is attached 10 a metal plug, I.

J J' are the carbon filaments, the combined resistance of which will be greater than that of the single carbon in the lamp B. These 15 filaments are connected at one end with the platinum terminals through their arms, and at the other end to the fusible strip H' at different points, so that the current when temporarily passing between them will fuse it, and so allow the plug I to be dropped into and be 20 held between the contacts G G', thus automatically closing the alternate branch circuit between such contacts and their connections with the main line and keeping same intact.

K is the key for cutting the lamp in and 25 out by hand. It consists of the flat strip of spring metal, k, faced with rubber or other insulator, k', pivoted to stud k², (also suitably shielded with insulating material,) which is 30 screwed through a projecting portion of the body into contact with the metal connecting-bar P. A coiled spring, k³, is wound around the stud k², has one end secured to the key and the other to the body A, and tends to keep the key in the position shown while the lamp 35 is cut in, besides insuring a very sudden lift at the moment that takes place.

To cut the lamp out, the key is depressed down upon and springs under the metal latch O, which, as will be seen in Fig. 3, communi-

cates with the connecting-piece N, and so 40 closes the circuit. A² is a shield of insulating material to prevent accidental touching of such latch.

What I claim is as follows:

1. In combination with an incandescent 45 electric lamp, an independent glass lamp-bulb, contact-pieces, and carbons of a higher resistance than that of the filament in the lamp proper, inclosed in such independent bulb, connections of carbons and contact-pieces 50 with main wires, a wire inclosed in and suspended from top of said independent bulb, a fusible strip forming part of such wire, to which said carbons are connected, and a drop-plug carried by said wire and adapted when 55 dropped to rest on said contact-pieces and form a circuit through them, all as herein set forth, and for the purpose described.

2. In an incandescent electric lamp, the combination, with the main wires m m and 60 connecting-strips l l, of the three armed insulated connecting-pieces P N, secured to the holder-body A, split to receive said strips l l, and the strips c c, connected respectively to terminals b b and F F', and the screwed 65 sleeves P' N', for securing the several parts firmly in place, as set forth.

3. In an incandescent electric lamp, the combination, with the main wires m m and connecting-pieces P N, of stud k², communicating with connecting-piece P, coiled spring k³, latch O, in contact with connecting-piece N, and key K, all carried by holder-body A, as shown and described.

EDWIN RUTHVEN WHITNEY.
